UNITED STATES PATENT OFFICE.

LANDY D. EPPERSON, OF MOUNT WASHINGTON, MISSOURI.

COMPRESSING MECHANISM FOR ROTARY INTERNAL-COMBUSTION MOTORS.

1,404,354.

Specification of Letters Patent. Patented Jan. 24, 1922.

Application filed August 16, 1920. Serial No. 404,028.

To all whom it may concern:

Be it known that I, LANDY D. EPPERSON, citizen of the United States, and resident of Mount Washington, Jackson County, Missouri, have invented a certain new and useful Improvement in Compressing Mechanism for Rotary Internal-Combustion Motors, of which the following is a complete specification.

10 This invention relates to compressing mechanism for rotary internal combustion motors, and my object is to produce simple and efficient mechanism of the character indicated in which a plurality of compression 15 pistons successively compress combustible mixture for different firing chambers where it is exploded for applying force to a shaft a plurality of times in a single revolution thereof and thereby insure high speed and 20 smooth operation of the engine.

A further object is to produce means which shall operate economically and insure charges of combustible mixture almost pure, by effecting a substantially thorough 25 evacuation of the burned gases. A still further object is to produce mechanism of few parts and of compact and relatively inexpensive construction, and an engine, which if muffled at the exhaust points, will be 30 practically noiseless in operation.

With these objects in view, the invention consists in certain new and useful features of construction and combinations of parts as hereinafter described and claimed; 35 and in order that it may be fully understood, reference is to be had to the accompanying drawings, in which:

Figure 1 is a horizontal section taken on the line I—I of Figure 2, with certain parts 40 shown in full line.

Figure 2 is a side elevation with certain parts shown in section and others broken away to disclose mechanism otherwise hidden.

45 Figure 3 is a vertical section taken on the line III—III of Figure 4.

Figure 4 is a section taken on the line IV—IV of Figure 3.

Figure 5 is a detail perspective view of 50 one of the oscillating valves of the invention.

In the said drawings, 1 is a cylinder divided by a central partition into chambers 2 and 3 respectively occupied by pistons 4 and 5, connected together by a tie-bolt 6 extending slidably through the said partition

with a leak-proof relation. Pivoted at 7 to the piston 5, is a connecting rod 8, pivotally connected at its opposite end to the crank of a crank-shaft 9, journaled in a pair 60 of bearings 10 secured to the said cylinder, and in a supplemental bearing 11, supported in a manner hereinafter referred to.

12 and 13 are circular casings or cylinders disposed at opposite sides of the cylinder 1, 65 and extending axially through said cylinders and suitably journaled therein, is a shaft 14, equipped at one end with a gear-wheel 15, meshing with a gear-wheel 16 on the adjacent end of the crank shaft 9. For convenience, the bearing 11 is secured to the casing 12.

The casings 12 and 13 are provided with circular channels 17, and within said casings are discs 18 mounted on shaft 14 and rotatable 75 therewith, the discs being provided with arcuate pistons 19, fitting snugly in and partitioning said channels.

Between said casings 12 and 13 is a connecting portion 20 provided with firing 80 chambers 21 respectively communicating with said casings so that at the proper time, power produced through explosion of the combustible mixture, may be provided to impel or drive the said pistons of said disks, 85 as hereinafter particularly explained.

Each of said casings 12 and 13 is provided with an exhaust port 22 for the escape of burned or dead gases from the channel 17; said exhaust port bearing such relation to 90 the intake ports of said casings and the length of the pistons 19, that when the former are beginning to be bridged by said pistons, the latter have partly unbridged or uncovered the said exhaust ports. In this 95 connection, it is to be understood that the pistons of said cylinders are disposed at diametrically opposite points with respect to the axis of shaft 14, so that there shall be an explosion for applying force to each 100 piston in each revolution of the shaft 14, as will hereinafter appear.

Associated with cylinders 12 and 13 respectively are similar casings or cylinders 23 and 24 having annular channels 25 intersecting channels 17 of the casings 12 and 13, as shown clearly in Figure 2. The casings 23 and 24 are, like casings 12 and 13, provided with disks 26 and with rims or abutments 27, provided with notches 28. The rims 27 are 105 intended to seal or partition the channels 25 and the notches or spaces in said rims accom-

modate the said pistons, the arrangement being such that as a piston passes out of the notch of the rim or abutment 27 associated with it, and uncovers the intake port an explosion occurs and expends its force against the walls of channel 17, the periphery of the rim or abutment 26, and the rear face of the piston, as will be readily understood. To this special construction, no claim is made as the same is embodied and claimed in an allowed application filed April 21, 1919, Serial Number 291,481. As in said application, the disks 26 are mounted upon a common shaft 29, and power is transmitted to said shaft by a gear wheel 30 on shaft 14 meshing with a similar gear wheel 31 on shaft 29.

At opposite sides of the central partition of cylinder 1, are intake ports 33 and 34 respectively for cylinders 3 and 2, and mounted upon the cylinder over said ports 33 and 34 is a valve casing 35, provided with a segmental chamber 36, and with a pair of ports 37 and 38 communicating respectively with ports 33 and 34. A tubular connection 39, preferably elbow shaped, communicates with and closes chamber 36, and is adapted for connection with a carburetor not shown. A cross shaft 40 is journaled in bearings formed by casing 35 and connection 39 and is equipped within chamber 36 with a valve 41, provided with a central port for alternate engagement or communication with ports 37 and 38. At one end, shaft 40 is provided with a depending crank arm 43 connected by a rod 44 with an eccentric 45 mounted on shaft 9, so that the operation of said shaft shall, through said connection, effect the operation of valve 41 and the alternate supply of combustible mixture to chambers 2 and 3. The cylinder 1 is provided with an opening at its lower side divided by a partition 46 into discharge ports 47 and 48, the cylinder being formed with depending flanges which cooperate with partition 46 in producing said discharge openings or ports 47 and 48, which ports it will be noticed by reference to Figures 1 and 3, respectively communicate with chambers 3 and 2 of the cylinder.

A partitioned casing 49 underlies the compression cylinder 1 and cooperates with the depending flanges thereof above mentioned and partition 46 in providing a pair of segmental valve chambers 50 and 51 containing oscillatory valves 52 and 53 respectively, said valves being mounted on a transverse shaft 54 journaled in the said cylinder flanges and partition 46, and in said casing 49, packing boxes 55 preventing leakage of gas around the shaft.

Secured on and projecting upward from one end of shaft 54 is a crank arm 56 pivotally connected by a rod 57 with an eccentric 58 on shaft 9. Each firing chamber is provided with a spark plug 59.

With the parts occupying the respective positions shown, and the crank shaft operating in the direction indicated by the arrow, Figure 3, it will be apparent that piston 5 is about to begin its suction stroke and piston 4 its compression stroke; that valve 41 is moving to open communication through ports 42, 37 and 33, between the carburetor and chamber 3, and that valve 53 is moving to open communication through ports 48, 75 and valve port 60, between chamber 2 and the firing chamber 21 of cylinder 13. At this time, the piston 19 of cylinder 13, has closed the intake port of said cylinder and remains closed until the compression stroke of piston 4 is completed, and as this stroke ends, piston 19 begins to open the said intake port. When said port is about half opened, a spark is produced to explode the charge and thus drive shaft 14. When said shaft has completed about a half revolution, the piston 5 has completed its ensuing compression stroke and piston 4 has completed its ensuing suction stroke, and is prepared to compress the charge from chamber 2 into the firing chamber of cylinder 12, the intake port of which is closed at the time, by the piston 19 of said cylinder, and as said piston opens said port, ignition occurs to produce an explosion in cylinder 12 and apply force a second time to shaft 14 in one revolution thereof. All future operations are repetitions of those described, it being noted that the valves oscillate together in the same direction and that the ports between the compression cylinders 90 and the firing chambers are so direct and short that a substantially complete scavenging operation of dead gases is effected. It will also be noted that there is no waste of gas as leakage from one compression cylinder 105 around the rod 6, is retained by the companion cylinder.

From the above description, it will be apparent that I have produced a compressing mechanism for rotary internal combustion engines embodying the features of advantage set forth as desirable in the statement of the object of the invention, and while I have illustrated and described the preferred embodiment of the invention, it is to be understood that changes in the form, proportion, detail construction and arrangement of the parts, may be resorted to without departing from the principle of construction involved or sacrificing any of the advantages 110 of the appended claims.

I claim:

1. A compressing mechanism for internal combustion motors, comprising a partitioned cylinder, a pair of connected operating pistons one in each chamber of the cylinder, a valve casing for the supply of gaseous mixture, in communication with both chambers of the cylinder, and a valve operated back and forth in timed relation with the pistons 125 130

to close communication between the valve casing and one of said chambers and open communication between said casing and the other chamber in one operation, and to reverse such conditions in the reverse operation.

2. A compressing mechanism for internal combustion motors, comprising a partitioned cylinder, a pair of connected operating pistons, one in each chamber of the cylinder, means for supplying gaseous mixture alternately to said chambers for compression by said pistons respectively, a pair of discharge ports in said cylinder walls respectively, a pair of chambers respectively communicating with said ports and having discharge ports, and valve mechanism operated in said last-named chambers in timed relation to the pistons, to open communication between one of the piston chambers and one of said last-named discharge ports, and close communication between the other piston chamber and the other of said last-named discharge ports, in one operation, and to reverse such conditions in the reverse operation.

3. A compressing mechanism for internal combustion motors, comprising a partitioned cylinder, a pair of connected operating pistons, one in each chamber of the cylinder, means for supplying gaseous mixture alternately to said chambers for compression by

said pistons respectively, a pair of discharge ports in said cylinder walls respectively, a pair of chambers having discharge ports, a pair of valves within said chambers for controlling communication between said cylinder ports and the discharge ports of said last-named chambers in timed relation to said pistons, one of the valves opening communication between one of the piston chambers and one of said last-named ports as the other valve closes communication between the other piston chamber and the other of said last-named ports.

4. A compressing mechanism for internal combustion motors, comprising a pair of aligned piston chambers, a pair of connected pistons in said chambers respectively, a valve chamber above and a pair of valve chambers below said piston chambers, the first-named valve chamber having a pair of ports respectively connected to said piston chambers, and said pair of valve chambers being each connected to one of said piston chambers, a valve in the first-named valve casing and a pair of connected valves in said pair of valve casings, means for oscillating the first-named valve, and means for oscillating said pair of valves.

In testimony whereof, I hereunto affix my signature.

LANDY D. EPPERSON.
